UNITED STATES PATENT OFFICE.

OSCAR R. MANVILLE, OF BRECKENRIDGE, MISSOURI.

SHOVELING-BOARD.

1,209,866.

Specification of Letters Patent. Patented Dec. 26, 1916.

Application filed April 22, 1916. Serial No. 92,933.

To all whom it may concern:

Be it known that I, OSCAR R. MANVILLE, a citizen of the United States, residing at Breckenridge, in the county of Caldwell 5 and State of Missouri, have invented a new and useful Shoveling-Board, of which the following is a specification.

The present invention appertains to shoveling boards for wagons, and aims to provide 10 novel and improved means for applying a shoveling board to the rear end of a wagon body for holding the shoveling board in operative position, and for holding it in closed position so that it serves as an end gate for 15 the wagon body.

It is also the object of the invention to provide a device of the nature indicated which is extremely simple and inexpensive in construction, which can be applied to various 20 wagon bodies, and which will serve its purposes in a thoroughly satisfactory and practical manner.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed can be made within the scope of what is claimed without departing from the spirit of the invention.

The invention is illustrated in the accompanying drawing, wherein:

Figure 1 is a longitudinal section taken on the line 1—1 of Fig. 2. Fig. 2 is a plan view showing the shoveling board in operative position, portions being broken away. Fig. 3 is a rear view showing the shoveling 40 board in position to serve as an end gate. Fig. 4 is a sectional detail taken on the line 4—4 of Fig. 3.

In the drawing, the numeral 1 designates the shoveling board proper, which can be 45 constructed of wood, metal or other suitable material, and which is provided with the upstanding sides 2. This shoveling board 1 is applied to the rear end of the wagon body including the bottom 3 and 50 sides 4.

As a means for applying the shoveling board to the wagon body, a pair of upright angle irons 5 are applied to the upright cleats 6 secured to the rear ends of the sides 4 upon the inner surfaces thereof, so that 55 the angle irons 5 fit said cleats, as seen in

Fig. 2, and the angle irons can be bolted or otherwise fastened, as at 7, to the cleats and sides 4, whereby to provide a rigid structure. The angle irons 5 project upwardly above 60 the sides 4. Riveted or otherwise attached to the lower ends of the angle irons 5 adjacent the bottom of the wagon body, are plates 8 provided with depending hangers or shanks 9 projecting downwardly past the 65 rear end of the bottom 3, and provided at their lower ends with rearwardly projecting hooks 10 upon which the forward or lower edge of the shoveling board 1 seats. A transverse cleat 11 is secured to the lower 70 or rear surface of the board 1 adjacent the lower edge thereof, and is provided with a curved surface seating in and snugly fitting the hooks 10, whereby to effectively support the shoveling board, and to hingedly support 75 it adjacent the rear end of the bottom 3. The upper or forward face of the board 1 has grooves 12 for receiving the hangers 9 when the board 1 is swung to a vertical position against the rear ends of the sides 4, 80 whereby to provide a tight closure or end gate for the wagon body. The sides 2 of the shovel board overlap the outer surfaces of the sides 4 of the body.

As a means for supporting the shovel 85 board when in operative position, as seen in Figs. 1 and 2, inwardly projecting plates or bars 13 are riveted or otherwise secured to the angle irons 5, and have engaged therethrough bolts 14 upon which are threaded 90 nuts 15 seating against the plates 13. Said plates are preferably spaced above the sides 4 of the wagon body, and the rear ends of the bolts 14 have eyes 16 to which are loosely engaged the terminal eyes or loops 17^a of a 95 pair of resilient rods 17. These rods 17 project through apertures 18 provided in the board 1 and a transverse cleat 19 secured to the lower or rear surface of said board adjacent the free edge thereof. Plates or rings 21 are secured to the cleat 19 and have apertures 22 registering with the apertures 18 through which the rods 17 project, and the free ends of the rods 17 have rings or loops 20 upon which the plates 21 are seatable 105 when the shoveling board is swung downwardly to shoveling position, whereby to facilitate the loading or unloading of the wagon. The rods 17 thus provide hangers for suspending the free portion of the shoveling board from the angle irons or posts 5, and when the shoveling board is swung up- 110

wardly to closed position, to provide the end gate, the bolts 14 project through the apertures 18, whereby the rods 17 can be swung in back of the shoveling board for holding it tightly against the rear end of the wagon body.

Each plate 21 has a rearwardly projecting shoulder 23 below which is a cam surface 24, and a bar 25 is secured to the cleat 19 between the plates 21 and is provided with a downwardly projecting hook 26. Thus, when the board 1 is in closed position, the rods 17 can be swung toward the opposite sides and engaged under the hook 26, and can then be sprung over the shoulders 23, whereby the rods will bear upwardly against the hook 26 and will bear downwardly upon the shoulders 23, to force the board or end gate onto the hooks 10 and against the sides 4 and bottom 3 of the wagon body by spring tension. This prevents the rattling or vibrating of the shovel board. The cam surfaces 24 facilitate the upward movement of the free portions of the rods 17 onto the shoulders 23, as when the rods 17 are moved under the hooks 26 and then slid upwardly along the cam surfaces 24 to the shoulders 23.

From the foregoing, it is believed that the advantages and attributes of the invention

will be obvious to those versed in the art, without further comment being necessary.

Having thus described the invention, what is claimed as new is:

A device of the character described comprising a pair of posts attachable to the rear ends of the sides of a wagon body, a shoveling board hingedly connected with the rear ends of said posts, said shoveling board having apertures adjacent its free portion, members attached to said posts to project through said apertures when the board is swung upwardly, resilient rods loosely connected with said members and projecting through said apertures, said rods having portions at their free ends for supporting the board when it is swung downwardly, plates attached to the board having shoulders, and a member carried by the board between said plates under which the rods are engageable when the board is swung upwardly, the free portions of said rods being seatable upon said shoulders.

In testimony that I claim the foregoing as my own, I have hereto affixed my signature in the presence of two witnesses.

OSCAR R. MANVILLE.
